UNITED STATES PATENT OFFICE.

E. A. MOORE, SAMUEL MOORE, AND DAVID MOONEY, OF FINDLAY, OHIO.

IMPROVEMENT IN CATTLE-PUMPS.

Specification forming part of Letters Patent No. 33,848, dated December 3, 1861.

To all whom it may concern:

Be it known that we, E. A. MOORE, SAMUEL MOORE, and DAVID MOONEY, all of Findlay, in the county of Hancock and State of Ohio, have invented a new and Improved Pump to be Operated by Stock; and we do hereby declare that the following is a full, clear, and exact description of the same, reference being had to the annexed drawings, making a part of this specification, in which—

Figure 1 is a vertical central section of our invention, taken in the line xx , Fig. 2; and Fig. 2 a plan or top view of the same.

Similar letters of reference indicate corresponding parts in the two figures.

The object of this invention is to obtain a simple and efficient pump by which stock may draw their own supply of water for drinking purposes.

The invention consists in the employment or use of a force-pump in connection with a loaded or counterpoised tilting platform, constructed and arranged substantially as hereinafter fully shown and described, whereby the desired result is attained.

Pumps or water-elevators of this class, commonly termed "stock-pumps," should be so arranged as to preclude the possibility of freezing up in winter, and at the same time admit of the water being elevated to a considerable height. They should be simple in construction and not liable to get out of repair, and the pump-cylinder should always be filled with water beneath the piston when the latter is elevated, so that as soon as the piston begins to descend under the action of the weight of an animal, water will be ejected from the nozzle or spout. These ends, it is believed, are fully attained by the herein-described invention.

To enable those skilled in the art to fully understand and construct our invention, we will proceed to describe it.

A represents a well or reservoir from which water is to be drawn by our invention.

B is a pump-cylinder, which may be of wood or metal. This cylinder extends down to the bottom of the well or reservoir, and is secured thereto in any proper way. The lower part of the cylinder B is perforated, as shown at a , Fig. 1, and within the cylinder, just above the

perforations, there is placed a valve C, opening upward.

D is the piston, which is fitted in the cylinder B above the valve C, and is connected by a joint b with its rod E. The piston is not provided with a valve, but a valve c opening outward is placed in the upper part of the side of the cylinder just below the head d .

F represents the eduction-pipe of the pump. This pipe is attached to the cylinder B just above the valve C, and is provided with a ball-valve G opening upward. The eduction-pipe F has a joint e just above the valve G to admit of the upper part being detached, when necessary. This upper part extends above the top of the well or reservoir, and comes downward so as to allow the water to be discharged into a trough which may be arranged in any proper way.

H is a framing, which is placed on the well A, and on which a platform I is fitted or hung on pivots ff . This platform I has a weight J' on its outer part, and the inner part of the platform has the end of a bar or lever J fitted loosely into it, as shown clearly in Fig. 1. The bar or lever J at its outer end is secured by a pin g in an upright K, and is allowed to rock freely thereon. The inner end of the bar or lever J has a rope or chain L attached, which passes over pulleys h in a horizontal bar M, secured to the upper end of the upright K. The rope or chain L has a weight N at its outer end.

The upper end of the piston-rod E is attached to the inner end of the bar or lever J .

The operation of the pump is as follows: The weight J' at the outer end of the platform I and the weight N at the end of the rope or chain L have a tendency to keep the inner part of the platform I, and consequently the piston D, in an elevated state. When an animal passes on the platform I and toward its inner end, the piston D of course will be depressed, and the water in the cylinder B will be forced up through the pipe F, as indicated by the arrows, and the animal will have a supply of water. When the animal passes off the platform, its inner end is elevated under the action of the weights J N , and the piston D rises and causes the cylinder B to fill with water, the valve C of course opening and the

valve G of the pipe F closing. The valve G it will be seen retains the water in the eduction-pipe F, and as the piston D, in ascending under the action of the weights, causes the cylinder B to be filled with water, which is retained in the cylinder of the valve C, it follows as a matter of course that water will be ejected from the tube F simultaneously with the descent of the piston.

During the winter season when the pump is not in use, the pipe F may be detached at its joint e, in order to prevent the freezing up of the pump. It will be seen, however, that when required at any time the pipe F may be very readily applied.

We do not claim separately any of the parts, irrespective of the combination and arrangement herein shown and described, for tilting

platforms have been previously used for the purpose.

We claim, therefore, as new and desire to secure by Letters Patent—

The arrangement of the tilting platform I and bar or lever J, loaded as shown, in combination with the force - pump partially or wholly submerged and provided with the jointed elevation - tube F, valves C G, and solid or close piston D, as and for the purpose herein set forth.

E. A. MOORE.
SAMUEL MOORE.
DAVID MOONEY.
